UNITED STATES PATENT OFFICE.

NELSON C. MARKHAM, OF DENVER, COLORADO.

GRINDER AND POLISHER FOR CAR-JOURNALS.

1,083,452.

Specification of Letters Patent.

Patented Jan. 6, 1914.

Application filed April 23, 1913. Serial No. 763,123.

To all whom it may concern:

Be it known that I, NELSON C. MARKHAM, a citizen of the United States, residing at Denver, in the city and county of Denver and State of Colorado, have invented certain new and useful Improvements in Grinders and Polishers for Car-Journals, of which the following is a specification, reference being had to the accompanying drawings.

This invention relates to new and useful improvements in the art of grinding and polishing and more particularly to a device for grinding and polishing car journals and the primary object of the invention is to provide a device of this character which may be used for grinding and polishing a journal without removing the same from the stuffing or packing box.

A further object of the invention resides in providing a device which may be adjusted over the journal and rotated therewithin the packing or stuffing box and a still further object resides in providing a device which is simple and durable in construction, inexpensive to manufacture and one which will be very efficient and useful in operation.

With these and other objects in view, the invention consists in the novel features of construction, combination and arrangement of parts as will be hereinafter referred to and more particularly pointed out in the specification and claims.

In the accompanying drawings forming a part of this application, Figure 1 is a side elevation partly in section showing my improved grinder and polisher applied to use. Fig. 2 is a front elevation of the journal box with my device applied to use therein and showing the drive shaft in section. Fig. 3 is a vertical longitudinal section through my improved device. Fig. 4 is a vertical transverse section therethrough as seen on line 4-4, Fig. 3, looking in the direction of the arrow; and Fig. 5 is a similar view as seen on line 5-5, Fig. 3 looking in the direction of the arrow.

In describing my invention, I shall refer to the drawings in which similar reference characters designate corresponding parts throughout the several views and in which 1 indicates a car journal mounted in a packing box 2, said journal within the packing box being provided with the usual collar 3.

My invention contemplates a means for

polishing and grinding the journal within the packing box and to this end, a trio of circular disks 4, 5 and 6 are provided, the same being of equal diameters and riveted or otherwise secured together. Each of said disks 4, 5 and 6 is provided with a central threaded opening so that when the same are brought together, a threaded bore 7 is provided to be engaged on the threaded end 8 of a drive shaft 9. These disks 4, 5 and 6, riveted together, as they are, form a head piece or the like for application to the drive shaft and said head piece is held against movement on the drive shaft by a lock nut 10. It might here be stated, however, that the free end of the drive shaft 9 is tapered conically as shown at 11, the purpose of which will be hereinafter and more particularly set forth.

The central disk 5 of the substantial head piece is provided with a trio of substantial radial slots 12, which lead from the peripheral edge of said disk and terminate at points adjacent the central opening thereof. The outer disk 4 is provided with a plurality of threaded screw openings 13 which are arranged in series of three openings each, each series being disposed over a slot 12 of the disk 5.

A trio of spring metal arms 14 are provided, each having its one end looped outwardly, as shown at 15 and bent to form a shank 16, the latter completing a substantial L, with the body of the arm. These shanks 16 of the spring arms 14 are adapted to be received in the slots 12 of the disk 5 when said latter disk is properly secured between the disks 4 and 6, and an offset portion formed between the loop 15 and the shank 16 of each of the spring arms forms a shoulder 17 which is adapted to abut the peripheral edge of the disk 6 to limit the movement of, and properly position each of said spring arms thereto. Set screws 18 are adapted to be engaged with the openings 13 in the disk 4 to bind against the shanks 16 and secure the same in position in the head piece.

An emery grinding strip 19 is provided for each of the spring arms 14, said strips 19 being secured to the inner opposed faces of said spring arms by means of the bolts 20 extending through slots 20' in the arms 14 and engaged by nuts 21. The inner faces 130 of said strips 19 are concaved, as shown at 22, and the heads of said bolts 20 are coun-

ter-sunk in said concaved faces, as clearly shown in the drawings, while the nuts 21 are engaged with the shanks of said bolts on the outer faces of said spring arms to secure 5 said strips 19 in position thereon.

In practice, to apply this device to use, the car is raised and supported by a jack, so that the weight of the car no longer rests upon the journal, and the packing is then 10 removed from the packing box. Assuming that the parts of my improved device are all set up, the arms 14 with the emery grinding strips thereon are adjusted over the collar 3 and the journal. The structure of the device is such that the arms will spring tightly 15 about said journal and the concaved inner faces 22 of the strips 19 will fit snugly thereon. The outwardly looped portions 15 of the arms 14 are, obviously, provided for the 20 reception of the collar 3 on the axle and a beveled recess is provided in the outer end of the axle at a central point thereon to receive the conical end 11 of the main drive 25 shaft 9. Power is then applied to said drive shaft through any desired means (not shown), which will, obviously, cause the head piece, formed by the disks, and the spring arms with the grinding strips thereon to be rotated on the end of the axle. This 30 rotation of the device will, obviously, grind and polish the journal to the desired extent. Of course, it will be understood that, although emery strips are described and shown in connection with the spring arms 14, strips 35 of other material, or in fact, other separate devices, may be applied to said arms for grinding and polishing purposes.

From the foregoing it will be seen that I have provided a simple, inexpensive and 40 efficient means for carrying out the objects of the invention and while I have particularly described the elements best adapted to perform the functions set forth, it is obvious that various changes in form, proportion and in the minor details of construction 45 may be resorted to without departing from the spirit or sacrificing any of the principles of the invention.

Having thus described this invention, 50 what is claimed is:—

1. A device of the class described comprising a disk-like head piece having a plu-

rality of radial channels therein, a plurality of angular spring arms having portions thereof disposed in the channels of said 55 head piece, means to secure the last mentioned portions of said angular arms in the head piece, a plurality of grinding strips secured to the inner faces of said spring arms, and supporting and driving means for 60 said head piece.

2. A device of the class described comprising a disk-like head piece having a plurality of radial channels therein, a plurality of arms looped and bent laterally at 65 their ends to form shanks thereon, said shanks being disposed in the radial channels of said head piece, means to secure the shanks of said arms in the head piece, the arms proper projecting from said head piece 70 being adapted for springing movement with respect thereto, a plurality of grinding strips removably secured to the inner faces of said projecting spring arms, the inner faces of said strips being concaved for engagement 75 with a curved surface, and a drive shaft removably engaged with the central portion of said head piece.

3. A device of the class described comprising a head piece composed of a trio of 80 disks suitably secured together, the central of said disks being provided with a plurality of radial slots to provide channels in said head piece, a plurality of angular spring arms having one of the bent portions thereof disposed in the channels of said head piece, means extending through one of the disks of said head piece and adapted for engagement with the last mentioned portions of the arms to secure the 90 latter to said head piece, grinding strips removably secured to the inner faces of the projecting portions of said spring arms, the inner faces of said grinding strips being concaved for engagement with a curved surface, and supporting and driving means for 95 said head piece.

In testimony whereof I hereunto affix my signature in the presence of two witnesses.

NELSON C. MARKHAM.
